SETTING FOR HYDRAULIC TURBINES

Application filed February 13, 1929. Serial No. 339,699.

The present invention relates to improvements in the settings for hydraulic turbines, and more especially to those of the vertical type and more particularly those of this type to which are connected superimposed electric generators.

The primary object of the invention is to provide a setting for hydraulic turbines of the vertical type which shall be efficient in operation but is less expensive in construction than those heretofore used. A more particular object is to provide a setting for hydraulic and electrical equipment which carries the weight and thrust present in the operation thereof directly and by compression to the foundation structure.

Further objects are to provide supports for the generator floor, or for the flume floor, or for both of these floors, which reduce the span thereof to one-half of that heretofore existing, and to provide the setting with a support for the turbine cover plate which will increase to a substantial degree the rigidity of the turbine structure and will relieve the gate mechanism of the turbine of the weight of the upper portion of the turbine.

The accomplishments of these objects will reduce substantially the cost of the setting by reducing the amount of concrete and reinforcement required under the generator or in the flume floor, or in both, and the setting will be more rigid notwithstanding that it may be made less massive than heretofore, and the rigidity thus attained will aid in reducing or eliminating vibration during the operation of the equipment.

In the accompanying drawings:—

Figure 1 represents a vertical section taken axially through a hydraulic turbine and superimposed generator provided with a setting constructed in accordance with one embodiment of the present invention;

Figure 2 represents a section taken horizontally through the flume and the hydraulic turbine on the line 2—2 of Figure 1;

Figure 3 represents a section taken horizontally through the tail pit shown in Figure 1, on the line 3—3 of that figure;

Figure 4 represents a vertical section taken through a portion of the flume, showing a

modification of the flume shown in Figures 1 to 3 inclusive;

Figure 5 represents a horizontal section taken on the line 5—5 of Figure 4;

Figure 6 represents a vertical section taken centrally through a portion of a turbine setting using an elbow draft tube instead of the tail pit shown in the preceding figures, and which may be used in conjunction with an electric generator setting such as that shown in the preceding figures; and

Figure 7 represents a horizontal section through the elbow draft tube setting shown in Figure 6, taken on the line 7—7 in that figure.

Similar parts are designated by the same reference characters in the several figures.

The present invention is applicable generally to hydraulic turbines of the vertical type, and it is more particularly applicable to hydro-electric equipment embodying a vertical hydraulic turbine and a superimposed electric generator, it providing a relatively strong and rigid support or mounting for the hydraulic turbine and the floor which supports it and providing a relatively strong and rigid support or mounting for the relatively heavy electric generator, to the weight of which is added that of the turbine runner and its shaft and the downward thrust acting on the turbine runner. The improved setting also provides a stronger and more rigid support for the generator floor which, in the preferred embodiment of the invention, supports the weight of the upper portion of the turbine and thereby relieves the gate mechanism and the lower portion of the turbine from the weight thereof.

In the embodiments of the invention shown in the accompanying drawings, 1 represents generally a hydraulic turbine of the vertical type having an axial flow runner 2 mounted on a vertical shaft 3, the runner being enclosed within a casing which includes a top plate 4 and a bottom plate 5, and the flow of water to the runner is controlled by an annular series of wicket gates 6 which are pivotally mounted between the top and bottom plates of the turbine casing by means of gate pins or pivots 7, the series of gates be-

ing connected together and operated or controlled by any suitable or well known gate operating or governing means which is well understood in the art and hence is not illustrated. The top plate 4 of the turbine is riveted or otherwise secured to the lower end of a barrel 8 which may be cylindrical in form and composed of plate steel or cast iron, this barrel being hollow and providing means of access to the upper bearings of the gate pins and other portions of the turbine. The bottom plate 5 of the turbine is connected to and supports a draft tube 9 through which the water discharges from the turbine.

15 The flume 10 which receives water from an intake 11 and supplies water to the turbine to operate it, embodies a pair of laterally spaced vertical walls 12 which are arranged to extend at opposite sides of the 20 turbine, a down-stream end wall 13 and a floor or deck 14, the latter surrounding the base of the turbine, these walls and deck being usually embedded in the ground and being composed of concrete with steel or other 25 reinforcement.

In the embodiment of the invention shown in Figures 1 and 3, a tail pit 15 is provided beneath the flume and its deck 14, the side walls of this pit being, for example, downward continuations of the side walls 12 which are arranged at opposite sides of the draft tube 9, the tail pit having a vertical upstream end wall 16 and a bottom wall 17, the latter constituting the foundation of the setting 30 35 and the downstream side of the tail pit leads to a tail race 18 through which the water discharging from the draft tube is conducted away from the turbine.

40 The water which enters the flume 10 from the intake 11 flows more or less tangentially into the turbine through the openings provided between the wicket gates 6 and acts on the runner 2 of the turbine to revolve it in the well known way, the course of the water being 45 diverted downwardly as it flows through the turbine and this axially flowing body of water descends through the draft tube and discharges from its outlet end into the tail pit or into a tail race.

50 In the turbine setting shown in Figures 1 and 3, employing the tail pit, the bottom plate 5 of the turbine and the draft tube 9 connected thereto are supported by the flume deck 14, the latter being provided for this purpose 55 with an annular collar 19 of concrete which surrounds the upper end of the draft tube beneath the bottom plate 5 and provides an annular supporting surface 20 on which the turbine bottom plate rests, the flume deck 60 thus supporting not only the water contained in the flume but also a portion of the weight of the turbine and the draft tube. Heretofore, it has been the practice to employ a clear width or space in the tail pit between the side 65 walls 12 thereof so that the flume deck 14 had

a span equal to the distance between these walls, but owing to the great length of the span, it has been necessary to make the flume floor of a massive construction and to employ a considerable amount of reinforcement 70 in its construction to enable the deck to sustain the very considerable load imposed upon its central or intermediate portion by the turbine and the weight of water in the flume.

The present invention provides relatively 75 inexpensive means for increasing the strength and rigidity of the flume deck above a tail pit, although the deck may be made less massive and may contain less reinforcement than has heretofore been the practice. According 80 to the present invention, upright piers 21 are provided which extend from the tail pit floor or foundation 17 up to the flume deck 14, these piers being constructed preferably of concrete which is integral with the flume deck 85 and tail pit floor. These piers are also preferably in a vertical plane which coincides with the vertical diametral plane of the draft tube 9 so that they extend in an upstream and a downstream direction in relation to the draft tube, and the piers are preferably located in a plane midway between the vertical side walls 12 of the tail pit. As shown, the upstream pier 21 extends to and joins the upstream end wall 16 of the tail pit 90 and it extends to the upstream side of the draft tube, and the downstream pier 21 extends from the downstream side of the draft tube to the tail race 18. These piers thus constitute rigid compression members in the median vertical plane of the flume deck and in the plane of the vertical axis of the turbine which reduce the span of the deck to one-half of that previously existing according to previous practice, and these piers consequently 95 strengthen the flume deck to a substantial degree so that the deck will be of ample strength to support the weight of the water in the flume, and weight of the turbine resting on the deck although the deck may be made less massive in construction and may contain less reinforcement, and these piers which extend from the deck to the tail pit floor or foundation render the flume deck more rigid and hence vibration incident to the operation of the equipment is thereby reduced or minimized.

100 While the piers 21 divide the tail pit substantially into two lateral compartments, they do not interfere appreciably with the flow of the water from the draft tube to the tail race, as the piers extend substantially in the direction of flow of the discharging water. Preferably the adjacent edges of these piers beneath the draft tube are nosed off as indicated at 21^a to reduce or avoid disturbance of or obstruction to the flow of the water discharging from the lower end of the draft tube. The upstream corners of the tail pit 105 may be left square or angular as shown at 110 115 120 125 130

16^a, or they may be rounded by filleting the concrete in these corners as indicated at 16^b in order to obtain smoother flow conditions of the water as it discharges into and flows

5 through the tail pit.

In an installation wherein a vertical hydraulic turbine is connected to a superimposed electrical generator, the concrete setting provides a generator supporting floor 22 which spans the space between the vertical walls 12 of the setting, this floor having an annular collar or base 23 formed as a part of it and providing a mounting on which the electrical generator 24 rests. In installations 10 of this kind, the electrical generator is usually provided with a bearing 25 which sustains the downward thrust due to the weight of the turbine runner and its shaft and the downward thrust of the water acting on the turbine 15 runner, so that the generator supporting deck 22 has imposed upon it not only the weight of the generator but also the downward thrust exerted upon it from the runner of the turbine. Heretofore it has been the practice to 20 construct the generator deck of concrete having steel or other reinforcement embedded therein and to construct the generator deck so that it would span the entire clear space between the vertical side walls 12 of the flume, 25 but in order to enable the generator floor to sustain the great load imposed upon it, it has been necessary heretofore to make the generator floor of a very heavy construction and to employ a great amount of reinforce- 30 ment therein. According to the present in- 35 vention, the generator supporting floor 22 may be made of concrete having suitable re- 40inforcement therein but a pair of piers 26 are extended from the flume deck 14 upwardly 45 to the generator supporting floor, these piers being preferably made of concrete and formed integrally with the flume deck and the generator supporting floor. These piers 26 are 50 preferably located centrally of the width of 55 the flume or midway between the vertical walls 12 thereof or so that they lie in the vertical diametral plane of the turbine, and they extend in an upstream and downstream 60 direction. Moreover, the vertical piers 26 65 in the flume are in vertical alinement with the vertical piers 21 in the tail pit, in the embodiment shown in Figures 1 and 3, and in this instance, these superimposed piers thus form 70 continuous or direct compression supports 75 which extend from the generator supporting 80 floor to the tail pit floor or foundation struc- 85 ture 17, and these compression supports are 90 able to sustain effectively the entire weight 95 and thrust of the electrical generator and the 100 turbine. As the piers 26 in the flume are 105 located between the vertical side walls 12 there- 110 of, they reduce the span of the generator sup- 115 porting floor to one-half of that existing in 120 settings as heretofore constructed so that in- 125 creased strength and rigidity of the generator

supporting floor are attained although the floor may be made of less massive construction and less reinforcement therein will be required.

In applying the invention to a turbine setting using an elbow draft tube instead of a tail pit as hereinbefore described, the annular collar 19 which provides the annular supporting surface 20 on which the turbine bottom plate rests, rises from the flume deck 14^a which is supported by a concrete or other foundation which contains the elbow draft tube 9^a the upstream end of which is surrounded by the annular collar 19 and the downstream or outlet end 9^b of which extends longitudinally or substantially so, to the usual or any suitable tail race or discharge, the downstream end of the elbow draft tube being flared laterally or horizontally, substantially as shown in Figure 7. The foundation beneath the flume floor or deck, at the upstream side of the elbow draft tube, may be relatively solid, as indicated at 21^a so that it will directly receive and effectively sustain the load from the upstream pier 26 in the flume and directly above it, while the portion of the foundation at the downstream side of the elbow draft tube directly below the downstream pier 26 in the flume will receive the load therefrom, the portion 21^b of this part of the foundation which spans the space above the outlet of the draft tube being relatively deep vertically and being sufficiently strong, in turbine units of the relatively smaller sizes, to effectually 100 sustain the load imposed upon it by the downstream pier 26 in the flume, which is directly above it. In turbine units of the relatively large sizes, it is preferable to provide a pier 21^c in the outlet of the draft tube to reduce the span thereof to one half of its width, this pier, as shown extending vertically from top to bottom of the draft tube outlet or discharge passage, preferably centrally between its side walls 9^c, as shown in Figure 7, and extending in a downstream direction so that it does not materially disturb or obstruct the discharge of water from the draft tube. Since this pier 21^c in the outlet of the draft tube is below and in the same vertical plane with the downstream pier 26 in the flume, said pier 21^c will transmit any load imposed upon it from the portion 21^b of the setting on which the downstream pier 26 rests, directly to the foundation of the setting.

It is to be understood that an elbow draft tube setting such as that described may be used in connection with the flume and the turbine and generator settings shown in Figures 1 to 6 inclusive, in place of the tail pit construction shown in those figures, the foundation of the setting around the elbow draft tube sustaining the loads from the flume floor and the turbine and from the electric generator through the piers in the flume, the tur-

bine and generator being otherwise mounted and operative as shown and described in Figures 1 to 6 inclusive. The annular generator support 23 carries all of the load of the generator and enables the piers 26 to take most of this load, and the annular turbine support 19 carries most of the load of the turbine casing and enables the piers 21 to take most of this load.

10 While the vertical piers 26 in the flume divide the flume substantially into two lateral chambers or compartments they will not interfere appreciably with the flow of the water from the flume into the turbine, as 15 these piers extend in an upstream and downstream direction or substantially in the direction of flow of the water. In order to equalize the flow of the water between the two equal divisions of the flume, spaces 27 20 may be left between the gates of the turbine and the portions of the piers adjacent thereto through which water may flow from one division or chamber of the flume to the other, or as an alternative or in addition to these 25 spaces 27, openings 28 may be extended through the piers 26 so that they provide intercommunication between the divisions of the chambers of the flume at opposite sides of these piers to permit equalization of flow 30 of the water therein.

The piers 26 are aligned in the flume so that the water passing along them and approaching the gates of the turbine will flow smoothly and breaking up or other disturbance of the 35 water will be avoided. The downstream corners of the flume may be left square as indicated at 13^a but it is preferable to fillet these corners with concrete as shown at 13^b in order to assist in insuring smoother flow of the 40 water to the turbine. Also, it is preferable to bevel or nose off the edges of the piers 26 adjacent or opposite to the turbine gates, as indicated at 26^a in order to direct the water smoothly to the turbine gates adjacent to the 45 piers, the bevels 26^a as shown in Figure 2 conforming approximately with the angles of the adjacent gates 6 when the latter are open.

The present invention also provides improved means for stiffening the barrel 8 and 50 for supporting it and the entire upper structure of the turbine, thus eliminating, in some instances, the necessity for a heavy cast metal speed ring such as has been heretofore used where maximum rigidity is required. Even 55 for installation in which it may be considered desirable to install a speed ring, this invention has important advantages because the proper strength and rigidity can be obtained with a lighter and therefore less expensive 60 casting. For this purpose, the concrete composing the generator supporting floor 22 is extended downwardly in the form of an annular collar 29 which surrounds the barrel 8 so that this barrel is embedded in this concrete extension from the generator support- 65

ing floor, and the barrel may be provided with a circumferential flange 30 to increase its rigidity and to firmly anchor the barrel in the concrete. As the barrel 8 is fastened at its lower end to the top plate 4 of the turbine, the top plate of the turbine and the upper structure carried thereby as well as the barrel will be rigidly and effectively supported by the downward extension 29 of the generator supporting floor without imposing this load upon the gate pins or pivots 7, so that these gate pins may act merely as bearing or supporting members for the wicket gates 6.

70 The present invention provides improved means for supporting a hydraulic turbine or a hydraulic turbine and a superimposed electrical generator whereby greater strength and rigidity are attained although the concrete setting may be made less massive and a less amount of reinforcement may be used, 75 and greater rigidity of the setting is attained so that vibration incident to the operation of the equipment will be reduced or eliminated, with a reduction in the cost of the power house construction or setting, and these results are accomplished without interfering with or disturbing the flow of the water to and from the turbine or otherwise impairing its efficiency in operation.

79 While the invention has been shown and described as applied to a hydraulic turbine and generator of one specific type, it is to be understood that the invention may be used in the usual types of open or closed concrete or masonry flumes.

80 I claim:—

1. A hydraulic turbine and electric generator setting comprising a flume to contain a turbine, a floor above the flume having a generator mounted thereon, and a pier arranged in the flume beneath said floor and having a portion thereof located substantially vertically beneath the periphery of the generator and supporting said floor and generator.

105 2. A hydraulic turbine and electric generator setting comprising a flume having side walls and a floor having a turbine mounted thereon, a generator supporting floor above said flume floor and having a generator mounted thereon, and pier means extending between said floors in the space between the side walls of the flume, said pier means extending into close proximity to the turbine and substantially vertically beneath the base of the generator to support the generator and the intermediate portions of the generator supporting floor from the flume floor.

115 3. A hydraulic turbine and electric generator setting comprising a flume having side walls and a floor for supporting a turbine therein, a generator supporting floor extending between the side walls of the flume above the latter and having an annular generator mounting thereon, and piers arranged in the 120

flume beneath said generator supporting floor and extending into positions substantially vertically beneath the generator mounting and supporting said floor and generator mounting between said side walls.

4. A hydraulic turbine setting comprising a flume having spaced side walls and upper and lower floors extending between them, the lower floor having a turbine mounted thereon, and the upper floor having a generator mounted thereon and piers extending between said floors in the space between the side walls of the flume and located at the upstream and downstream sides of the turbine mounting, said piers extending into close proximity to the turbine and into positions substantially vertically beneath the periphery of the generator.

5. A hydraulic turbine setting comprising a flume having spaced side walls and upper and lower floors, the lower floor having a turbine mounted on its upper side, and piers extending vertically between said floors in the space between the side walls of the flume and extending into close proximity to the turbine, said piers dividing the flume into lateral chambers at opposite sides of the turbine setting, intercommunication means being provided between said chambers for equalizing the flow of water therein.

6. A hydraulic turbine setting comprising a flume having spaced side walls, a flume floor having a turbine mounted thereon, an upper floor above the flume floor and extending between the side walls of the flume, and piers extending between the flume floor and the portion of the upper floor between said side walls and supporting said portion of the upper floor, said piers being located at the upstream and downstream sides respectively of the turbine and extending into close proximity to the turbine inlet, the portions of the piers adjacent to the turbine being nosed off to direct the water from the flume into the inlet of the turbine.

7. A hydraulic turbine setting comprising a flume having spaced side walls, a flume floor having a turbine mounted thereon, an upper floor above the flume floor and extending between the side walls of the flume, and piers extending in an upstream and a downstream direction in the flume between the flume floor and the upper floor and supporting the portion of the latter floor which lies between the side walls of the flume, said piers extending into close proximity to the turbine and substantially dividing the flume into chambers which lie at opposite sides of the turbine, and means at the downstream portions of said chambers for directing water from the respective chambers of the flume into the turbine.

8. A hydraulic turbine and electric generator setting comprising a flume and a turbine discharge passage below it, a flume floor be-

tween the flume and said discharge passage having a turbine mounted thereon, a generator supporting floor above the flume, and having a generator mounted thereon, a pier located in the discharge passage beneath the flume floor and supporting the portion of the flume floor which lies above it, and a pier in the flume extending between the flume floor and the upper floor in vertical alignment with said flume floor supporting pier and extending into a position in close proximity to the turbine and substantially vertically beneath the periphery of the generator and supporting the portion of the upper floor which lies above and the generator mounted on said floor.

9. A hydraulic turbine setting comprising a flume and a turbine discharge passage beneath it, said flume and discharge passage having side walls, a turbine supporting floor between the flume and discharge passage, a floor above the flume and having a generator mounted thereon, and piers arranged in said flume and discharge passage between the side walls thereof and beneath the respective floors and extending into positions substantially vertically beneath the periphery of the generator, said piers supporting the generator and the floors between said side walls.

10. A hydraulic turbine setting comprising a flume, a tail pit beneath it, said flume and tail pit having spaced side walls, a turbine-supporting flume floor between the flume and tail pit and extending between said side walls, a floor above the flume and having a generator mounted thereon, and piers in the flume and tail pit between the side walls thereof and extending in an upstream and downstream direction therein and into positions substantially vertically beneath the periphery of the generator and supporting the generator and the portions of said floors which lie between said side walls.

11. A hydraulic turbine setting comprising a flume and a tail pit having spaced side walls, a foundation floor, a turbine supporting floor extending between said side walls above said foundation floor and having a turbine mounted thereon, a floor above the flume and having a generator mounted thereon, a draft tube extending downwardly from said turbine supporting floor into the tail pit, and piers extending between said floors between the side walls of the flume and tail pit and at the upstream and downstream sides of the turbine and draft tube and extending into positions substantially vertically beneath the periphery of the generator.

12. A hydraulic turbine setting comprising a flume and a tail pit having spaced side walls, a foundation floor, a turbine supporting floor extending between said side walls, above said foundation floor, a floor above the flume and having a generator mounted thereon a draft tube extending downwardly from

said turbine supporting floor and having an outlet above said foundation floor, and piers extending between said floors in the space between said side walls and at the upstream 5 and downstream sides of the turbine and draft tube, and also extending into close proximity to the upstream and downstream sides of the turbine and the outlet of the draft and into positions substantially vertically 10 beneath the periphery of the generator, the portions of said piers adjacent to but below the outlet of the draft tube being nosed off.

13. A hydraulic turbine setting comprising a tail pit having spaced side walls and a 15 tail race leading therefrom, a turbine supporting floor extending between said side walls, a draft tube extending downwardly from said floor into the tail pit and having an outlet near the bottom of the pit, piers 20 for supporting said floor located in said pit centrally between its side walls and joining with the upstream and downstream sides respectively of the draft tube and substantially 25 dividing said pit into lateral chambers, and means for directing water discharged into said chambers from the draft tube outlet to the tail race.

14. A hydraulic turbine setting comprising a flume, a tail pit beneath it having a 30 foundation floor, the flume and tail pit having side walls, a flume floor between the flume and tail pit and extending between said side walls, said flume floor having a turbine mounting on its upper side, an upper 35 floor extending between said side walls for supporting the upper portion of the turbine independently of said turbine mounting, a generator mounted on said upper floor, piers in the tail pit between its foundation 40 floor and the flume floor and supporting the latter between said side walls, and piers in the flume between the flume floor and the upper floor and aligned vertically with the piers first mentioned and supporting the 45 latter between said side walls, said piers in the flume and tail pit extending into positions substantially vertically beneath the periphery of the generator.

15. A hydraulic turbine and electric generator setting comprising a flume, a tail pit beneath it having a foundation floor, said flume and pit having laterally spaced side walls, a flume floor extending between said side walls and separating the flume and tail 55 pit, a turbine in the flume mounted on the flume floor, a draft tube extending downwardly from the flume floor into the tail pit, a generator supporting floor extending between said side walls above the flume floor and having a generator mounted thereon and connected to the turbine, and piers extending directly and continuously from the generator supporting floor to the foundation floor of the tail pit in the space between the 60 side walls of the flume and tail pit and hav-

ing portions thereof arranged substantially vertically beneath the periphery of the generator, said piers dividing the span of the generator supporting floor and flume floor between said side walls and supporting the 70 generator from the foundation floor.

16. A hydraulic turbine and electric generator setting comprising a flume, a tail pit beneath it and having a foundation floor, the flume and pit having spaced side walls, 75 a flume floor extending between said side walls and separating the flume and tail pit, a vertical axis turbine mounted on the flume floor and having a draft tube extending downwardly into the tail pit, a generator supporting floor extending between said side walls above the flume floor and supporting an electric generator connected to the turbine, and upright vertically aligned piers extending from the generator supporting floor to the foundation floor of the tail pit in the space between the side walls of the flume and pit and at the upstream and downstream sides of the turbine and draft tube and having portions thereof arranged in close proximity to the turbine and draft tube and substantially vertically beneath the periphery of the generator, said piers supporting directly the turbine and generator and the portions of the generator supporting floor and flume floor 90 which lie between said spaced side walls.

17. The combination of a turbine comprising a bottom plate and a draft tube extending downwardly therefrom, a top plate having a barrel connected thereto and extending upwardly therefrom, wicket gates pivotally mounted between said top and bottom plates, and a runner having a vertical shaft, an electric generator above the turbine and connected to the turbine shaft, and a concrete setting for the turbine and generator comprising a flume, a tail pit beneath it having a foundation floor, the flume and tail pit having laterally spaced side walls, a flume floor extending between said side walls and separating the flume and tail pit, said floor having a mounting thereon which supports the bottom plate and draft tube of the turbine, a generator supporting floor extending between said side walls above said flume floor and having a mounting thereon which supports the generator and also having a portion which embraces the barrel and supports it and the top plate of the turbine, and means extending into positions substantially vertically beneath the periphery of the generator for transmitting the load on the portions of the generator supporting floor and flume floor which lie between said side walls directly to the foundation floor of the tail pit.

In testimony whereof I have hereunto set my hand.

HARRY T. PORTER.
